DRY CLEANING MACHINE

Lossie E. Anderson, Chicago, Ill., assignor to
Standard Oil Company, Chicago, Ill., a cor-
poration of Indiana

Application June 30, 1932. Serial No. 620,144

5 Claims. (Cl. 68—38)

My invention relates to a novel system for the dry cleaning of garments in the home.

One object of my invention is to provide a very inexpensive and compact dry cleaning system suitable for domestic use. Another object is to provide a dry cleaning system of the above-mentioned type comprising an outer container to be used as a chamber for the dry cleaning operation and also as a shipping package for the dry cleaning equipment and dry cleaning fluid. Still further objects will become apparent as the description proceeds.

The method by which I have achieved these objects may be illustrated by reference to the accompanying drawing, in which Figure 1 represents a sectional view of my dry cleaning system assembled for shipment; Figure 2 represents a plan view of the inner container shown in Figure 1; and Figure 3 represents a sectional view 20 of my dry cleaning system in operating position.

Referring further to the drawing, my dry cleaning system as packed for shipment comprises an outer vessel 11, preferably a cylindrical metallic can, having a wide-mouthed opening 12 into which fits a closure 13. Said closure 13 carries a centrally located internally disposed bushing 14 or other suitable bearing means for rod 19. As shown, closure 13 is of the friction type having a U-shaped spring-like edge portion 15. Any other type of closure could suitably be used. Vessel 11 is equipped with swinging handles 16 for the convenience of the user.

Packed within the chamber formed by vessel 11 and closure 13 are an inner container 17, a plunger 35 or agitating device 18, an operating rod 19 having a handle 20, and a corrugated paper board cylinder 21 adapted to keep the various interior parts from damage during shipment. Operating rod 19 is packed with its lower end in the space between container 17 and vessel 11.

Inner container 17 as shown in Figures 1 and 2 is a cylindrical can adapted to serve as a package for dry cleaning fluid. This container is equipped with a metallic handle 22 for easy removal from vessel 11. Container 17 is also equipped with a pouring spout 22 and a closure cap 23.

My dry cleaning system is received by the user in the condition shown in Figure 1. In order to put it into operation, closure 13 is removed and paper board cylinder 21, plunger 18, inner container 17 and operating rod 19 are taken out of vessel 11. A suitable portion of the dry cleaning fluid shipped in inner container 17 is then placed in vessel 11 together with the garments which it is desired to dry clean. Operating rod 19 is

then slipped through bushing 14 in which it is adapted to operate in a vertical direction. Screw threads 25 at the bottom of operating rod 19 are next inserted in the corresponding screw threads in the neck 26 of plunger 18. Closure 13 is then replaced in opening 12 of vessel 11 and dry cleaning is accomplished by raising and lowering handle 20. This causes plunger 18 to coagitate the dry cleaning fluid and the garments being dry cleaned. When plunger 18 is raised it creates a suction effect, which causes the fluid to rush through the garments, facilitating rapid and thorough dry cleaning. On the down stroke the fluid again passes through the garments.

I have found that by this means it is possible to furnish a highly satisfactory home dry cleaning machine together with a package of dry cleaning fluid of the high priced non-flammable type at a total retail price which is not greatly in excess of the retail price of the same cleaning fluid as sold in a simple container which cannot be used for dry cleaning.

Although I have described my invention in connection with certain specific embodiments thereof, I do not wish to be limited thereby but only by the scope of the appended claims in which I have set forth the elements of novelty in my dry cleaning system.

I claim:

1. A portable home dry cleaning machine, comprising: a vessel; a removable closure for said vessel, said closure and said vessel forming a chamber; an agitating device; a handle and operating rod for removable attachment to said agitating device, said agitating device, handle and operating rod all completely disposed within said chamber; and means located in said closure to cooperate with said operating rod to permit the operation of said agitating device by means of said handle from outside said chamber; said agitating device, operating rod and handle when attached together having a maximum dimension in excess of the inside vertical dimension of said chamber, the minimum distance from the bottom of said agitating device, when attached to said operating rod and handle, to the bottom of said handle being slightly less than the vertical distance from the inside bottom of said chamber to the outside top thereof.

2. A portable home dry cleaning system, comprising: a vessel; a removable closure for said vessel, said closure and said vessel forming a chamber; an inner container disposed completely within said chamber; an agitating device disposed completely within said chamber; a handle

and operating rod for removable attachment to said agitating device, said handle and operating rod disposed completely within said chamber and at least in part between said inner container and 5 an inner wall of said vessel; and means located in said closure to cooperate with said operating rod to permit the operation of said agitating device by means of said handle from outside said chamber; said agitating device, operating rod and 10 handle when attached together having a maximum dimension in excess of the inside vertical dimension of said chamber, the minimum distance from the bottom of said agitating device, when attached to said operating rod and handle, to 15 the bottom of said handle being slightly less than the vertical distance from the inside bottom of said chamber to the outside top thereof.

3. A portable home dry cleaning system, comprising: a vessel; a removable closure for said 20 vessel, said closure and said vessel forming a chamber; an inner container disposed completely within said chamber at the bottom thereof; an agitating device disposed completely within said chamber on top of said inner container; a handle 25 and operating rod for removable attachment to said agitating device, said handle and operating rod disposed completely within said chamber and at least in part between said inner container and an inner side wall of said vessel; and bearing 30 means depending from said closure to cooperate with said operating rod to permit the operation of said agitating device by means of said handle from outside said chamber; said agitating device, operating rod and handle when attached together 35 having a maximum dimension in excess of the inside vertical dimension of said chamber, the minimum distance from the bottom of said agitating device, when attached to said operating rod and handle, to the bottom of said handle 40 being slightly less than the vertical distance from the inside bottom of said chamber to the outside top thereof.

4. A portable home dry cleaning system comprising a vessel, a closure for the mouth of said vessel, said vessel and said closure forming a dry cleaning chamber, an inner container disposed completely within said chamber at the bottom thereof, an agitating device disposed completely within said chamber on top of said inner container, operating means for operating said agitating device from outside of said chamber through said closure, said operating means being disposed completely within said chamber and extending along the side of said inner container between said inner container and said vessel, and means disposed between said agitating device and said closure to inhibit relative motion of said inner container and said agitating device while disposed within said chamber.

5. A portable home dry cleaning system comprising a wide-mouthed vessel, a closure for the mouth of said vessel, said vessel and said closure forming a dry cleaning chamber, an inner container of dry cleaning fluid disposed completely within said chamber at the bottom thereof, a handle affixed to the top of said inner container, an agitating device of the suction plunger type 100 disposed completely within said chamber on top of said inner container and surrounding said handle, operating means for operating said agitating device from outside of said chamber through said closure, said operating means being disposed completely within said chamber and extending along the side of said inner container between said inner container and said vessel, bearing means for said operating means carried by said closure and disposed within said chamber, and means 110 disposed between said agitating device and said closure to inhibit relative motion of said inner container and said agitating device while disposed within said chamber.
